UNITED STATES PATENT OFFICE

2,023,196

HYDROMETER

Oscar H. Fairchild, Chicago, Ill., assignor to Universal Oil Products Company, Chicago, Ill., a corporation of South Dakota

Application November 21, 1930, Serial No. 497,117

2 Claims. (Cl. 265—45)

This invention relates to an improved hydrometer for determining the specific gravity of a liquid, and relates more particularly to determining the specific gravity of a stream of liquid maintained under substantially atmospheric, sub-atmospheric or superatmospheric pressures.

One of the objects of my invention is to provide an improved form of hydrometer, particularly useful in determining the specific gravity of a stream of liquid at any instant. For example, it is often advantageous to determine the character, with respect to specific gravity, of a hydrocarbon distillate from a pressure still or rerun still as an index to the operation of the still and to assist in regulating the quality of the distillate produced.

Various preferred constructions of the hydrometer adapted for use under superatmospheric, sub-atmospheric or atmospheric pressures are illustrated in the accompanying drawings, which are more or less diagrammatic, and in which,—

Fig. 1 is a sectional, side-elevational view of one form of my invention, designed for superatmospheric pressure operations;

Fig. 2 is a sectional, side-elevational view of a modified form of my invention, designed for atmospheric operations;

Fig. 3 is a sectional, side-elevational view of another modification of my device; and

Fig. 4 is a top plan view of the form of device shown in Fig. 3.

Referring to Fig. 1, there is shown a main or lower body portion 1, provided with a removable base or closure member 2, inlet pipe 3 and outlet pipe 4, for containing a liquid 5, the specific gravity of which is to be measured, and which fixedly engages a suitable support or bracket 6; and a secondary or upper body portion 7 in fixed relation with a suitable support or bracket 8. The body portions 1 and 7 may be constructed of any suitable material, preferably a metal, of sufficient strength to withstand any desired pressure to which the apparatus may be subjected. Positioned intermediate the upper body portion 7 and the lower body portion 1 is a glass tube 9, of sufficient strength and thickness to withstand any desired superatmospheric pressure.

An hydrometer 10, of any conventional type, depending upon the character of the liquid to be tested, may float in the liquid 5 within a chamber 11 of the body 1. The neck of said hydrometer 10 may extend upwardly through tube 9, into the upper body member 7, rendering it observable through said tube 9. If desired, a reinforcing shell (not shown), of any suitable material, pref-

erably metal, may be provided to surround said tubular glass 9, although a tubular glass member, concentric with the upper or neck portion of the hydrometer 10 to provide a restricted passage therebetween, will be sufficient for most pressures.

The upper and lower extremities of the tubular glass 9 are adapted to be disposed in non-leaking relationship at their point of juncture with the lower and upper body casings 1 and 7, respectively. To insure such non-leaking relationship, I may provide a packing 12, maintained under compression by means of packing glands 13. If it be desired to remove, or for any purpose change the tubular glass 9, this may be accomplished 15 by merely unscrewing the packing gland 13.

In order to insure a more accurate reading of the calibrations 14 on the neck of the hydrometer 10, I provide a hairline 15 on the tubular glass 9. To conveniently clean the inner surfaces of the tube 9, a plug 16 may be provided in the upper end of the member 7, the removal of which provides access to the interior of said tube.

In order to prevent lateral movement of the lower body portion of the hydrometer 10 situated 25 within the chamber 11, and a consequent binding of the neck of the hydrometer within the tube 9, I may provide a plurality of guiderods 17 which may, if desired, be mounted upon the lower closure member 2 of the body 1. The rods 17, 30 as can be readily seen, will confine the movement of the hydrometer 10 in a vertical direction. To prevent the body of the hydrometer 10 from adhering to said guiderods 17, the rods may preferably be constructed of a relatively frictionless 35 material, such as glass, or any highly polished, non-corrosive metal or an alloy of iron or steel. Any desired number of guiderods 17 may be employed, depending upon the size of the hydrometer to be guided, and the nature of the liquid 40 under test.

If it be desired to change the hydrometer 10, or repair or alter the guide rods 17, this may be accomplished by removal of the base or lower closure member 2 of the body portion 1.

At the upper limits of the casing 1, and adapted to receive the overflow of liquid from the chamber 11. I may provide a reservoir 18 and compartment 19 in communication with the chamber 11. Disposed within the reservoir 18 is a well 20, adapted to receive and hold a temperature measuring device 21, to indicate the temperature of the liquid under test. Temperature measuring device 21 may be of any conventional type, such as a thermometer or thermo-couple.

In order to control the liquid level in the chamber 11 and the reservoir 18, I provide a liquid level control device 22, adapted to be disposed at the entrance of the compartment 19, to thread-
5 edly engage and bridge the upper longitudinal wall of said compartment 19. Liquid level control member 22 may be raised or lowered, as desired, through movement of the downwardly extending rod or arm 23, by means of the handle
10 24. The arm or rod 23 is suitably packed, as shown at 25, said packing being compressed by movable gland 26. Suitable inlet and outlet ports 27 and 28 are provided in the liquid level control member 22, providing for passage of liquid there-
15 through.

In the modification shown in Fig. 2, and which may be employed in atmospheric pressure operations, substantially the same general type of apparatus is employed as in Fig. 1, with the exception
20 that the apparatus employed, may, if desired, be of a lighter and less expensive construction. In addition, the following differences appear:—

The liquid level in the chamber 11' of the casing 1' is maintained constant by means of the
25 permanent overflow or liquid level walls 29. Adapted to receive said overflow liquid, and arranged concentric with and surrounding the upper portion of the casing 1', and integral therewith, is a reservoir 30, from which overflow liquid
30 passes through outlet pipe 4, controlled by a valve (not shown).

Since lower temperatures may be employed in atmospheric operations, a suitable temperature measuring device 31, of any conventional type, may have its base immersed in the liquid in the reservoir 30. A suitable plug 32, readily removable from the casing 1' and through which the temperature measuring device 31 passes, is provided for supporting said device 31 in any desired position. The plug 32 may be of rubber or other resilient material, adapted for ready removal and replacement.

A tubular glass 33 of any desired thickness, may have its base suitably packed in a closure member 34, threaded for removal from the body or casing 1'. The closure member 34 is apertured throughout its central portion in order to provide for reception of the base of the tubular glass 33 through which the upper portion or neck of the hydrometer 10 may be disposed.

Extending vertically from said closure member 34, and parallel to said tubular glass 33, I may provide metal support rods 35, of any desired type, bearing horizontal metal closure cap
55 36 adapted to be disposed over and close the upper end of the tubular glass 33, the juncture of said closure member and tubular glass being suitably packed as at 37. The cap 36 is held in fixed relation with the tubular glass 33 by
60 means of the nuts or bolts 38, threaded to the rods 35.

The tubular glass 33 may be of any desired length when used in this modification of the invention, since the care incident to a pressure operation and the requirement as to strength and structure of the glass is not as important. For this reason, a wider range of observance of the calibrations 14' of the hydrometer 10 is possible. A suitable cleaning plug 39, of rubber or other resilient material, and which is readily removable from the cap 36, is provided in order to clean the interior surfaces of the tubular glass 33.

All of the principles of my invention are also embodied in Fig. 3, which is another modification thereof, capable of employment when superat-

mospheric pressures are used. It will be seen that the upper casing 1 of Fig. 1 has been dispensed with, and in lieu thereof, I may provide vertical rods 35', substantially similar to those shown in Fig. 2. The vertical rods 35', by means
5 of the bolts 38', secure a horizontal metal closure cap 40, bearing packing 41, to the upper end of the tubular glass 42, thereby insuring a non-leaking, pressure-resisting juncture.

Inasmuch as the apparatus illustrated in this modified form of the invention may be subjected to high temperatures and pressures, care must be taken in selecting a tubular glass member 42 of sufficient strength to withstand the desired pressures and temperatures; also, a suitable temperature indicating or recording device 43, either a thermometer or thermo-couple, or the like, must be selected to accord with such temperatures and pressures. For illustration, I have shown in this modification a temperature measuring device 43 with its base immersed in the liquid in the chamber 11', disposed within a suitable support 44 within the casing 1'. Obviously, any other conventional temperature indicating or recording device may be employed.

As an example of a method of operation of my device as represented in Fig. 1, liquid at any desired temperature, and under atmospheric, super-atmospheric, or sub-atmospheric pressure, enters the chamber 11 tangentially through inlet 30 pipe 3, controlled by a valve (not shown). This tangential entrance of the liquid into the chamber 11 imparts a swirling action thereto as it rises within said chamber, resulting in a revolving action or rotation of the hydrometer 10 to 35 prevent adhesion of its surfaces to the surfaces of the guiderods 17, rendering said hydrometer operative and insuring an accurate indication of the gravity of the liquid at the hair-line 15 on the glass tube 9, when the appropriate level of 40 the liquid has been reached.

Continuing its rise throughout the chamber 11, the liquid will ultimately overflow into the communicating reservoir 18 within which is disposed the well 20 containing temperature indicating device 21, through which medium a temperature reading is taken of the liquid under test. Governed by the height at which the liquid level control 22 may be set, the rising liquid, upon filling the reservoir 18, will continue in its upward travel until it has equalled the height of the liquid level control 22, and upon exceeding the level there set, will overflow into said liquid level control through port 27 and pass into compartment 19 through outlet ports 28 in said liquid level control. The liquid will flow out of said compartment 19 through outlet pipe 4, controlled by a suitable valve (not shown). It is thus apparent that a raising or lowering of said liquid level control 22 will result in a corresponding increase 60 or decrease in the liquid level maintained in the chamber 11 and reservoir 18.

To calibrate those embodiments of my invention shown in Figs. 1 and 3, a liquid of known gravity, at a given temperature, may be introduced into the chambers 11 or 11', and the liquid level may be so adjusted as to obtain registration of a datum point upon the calibrated neck of the hydrometer and the hairline. Obviously, all subsequent gravity readings, taken at the same 65 temperature, will be accurate with reference to said setting. In superatmospheric operation, relatively high temperatures may be employed, and hence a false gravity reading may be obtained which must be corrected for temperatures. To 70 75

obviate these subsequent corrections, the correction for a given temperature **may** be made by suitably adjusting the liquid level, and thereby gravity readings at the new temperature may be 5 read directly from the hydrometer.

When the device is used in connection with a distilling apparatus in which steam is used or if for any other reason the distillate or other oil undergoing gravity determination contains water, 10 a water trap of any well known type should be provided in the line leading to the gravity indicating device or a drain may be provided in the lower body portion of the device to permit the periodic removal of accumulated water.

15 I claim as my invention:—

1. A device for measuring the density of liquid comprising in combination, a liquid chamber having curved walls, an inlet and outlet for said chamber, an hydrometer disposed in said chamber and means associated with said inlet to introduce liquid tangentially to the walls of said chamber. 5

2. A device for measuring the density of liquid comprising in combination, a liquid chamber having curved walls, a liquid inlet disposed tangentially to the walls of said chamber to impart a rotary motion to the introduced liquid, a liquid outlet, and a rotatable hydrometer disposed in said chamber. 10
